US0D1050121S

(12) **United States Design Patent** (10) **Patent No.:** **US D1,050,121 S**
(45) **Date of Patent:** ** **Nov. 5, 2024**

(54) **GAMING MONITOR**

(71) Applicant: **LG ELECTRONICS INC.**, Seoul
(KR)

(72) Inventors: **Yeonjin Kim**, Seoul (KR); **Daihyung Ryu**, Seoul (KR); **Heeju Chang**, Seoul (KR); **Taejin Lee**, Seoul (KR)

(73) Assignee: **LG ELECTRONICS INC.**, Seoul
(KR)

(**) Term: **15 Years**

(21) Appl. No.: **35/515,498**

(22) Filed: **Apr. 26, 2022**

(80) **Hague Agreement Data**

Int. Filing Date: **Apr. 26, 2022**

Int. Reg. No.: **DM/220587**

Int. Reg. Date: **Apr. 26, 2022**

Int. Reg. Pub. Date: **Oct. 28, 2022**

(30) **Foreign Application Priority Data**

Nov. 23, 2021 (KR) 30-2021-0056062

(57) **CLAIM**

The ornamental design for a gaming monitor as shown and described.

DESCRIPTION

1.1: Front perspective view

1.2: Rear perspective view

1.3: Front

1.4: Rear

1.5: Left

1.6: Right

1.7: Top

1.8: Bottom

1.9: Enlarged view of portion "1.9" of Reproduction 1.2
The evenly-spaced broken lines indicate portions of the gaming monitor that form no part of the claimed design. The dot-dash broken lines in Reproductions 1.2 and 1.9 indicate the extents of the enlarged view and form no part thereof.

1 Claim, 9 Drawing Sheets
